UNITED STATES PATENT OFFICE

146,836

DESIGN FOR A HANDLE FOR HAND
LUGGAGE

Clifford Brooks Stevens, Milwaukee, Wis., assignor to Wheary Incorporated, Racine, Wis., a corporation of Wisconsin

Application January 17, 1946, Serial No. 125,638

Term of patent 7 years

(Cl. D87—2)

To all whom it may concern:

Be it known, that I, Clifford Brooks Stevens, a citizen of the United States residing at Milwaukee, in the county of Milwaukee and State of Wisconsin, have invented a new, original, and ornamental Design for a Handle for Hand Luggage, of which the following is a specification, reference being had to the accompanying drawing, forming part thereof.

I claim:

The ornamental design for a handle for hand luggage, as shown.

CLIFFORD BROOKS STEVENS.
